DESIGNS

No. 12,798

Mar. 7, 1882

UNITED STATES PATENT OFFICE.

ALFRED DWIGHT, OF SPRINGFIELD, MASSACHUSETTS.

DESIGN FOR A BLANK BILL-HEAD.

SPECIFICATION forming part of Design No. 12,798, dated March 7, 1882.

Application filed February 4, 1882. Term of patent 3½ years.

To all whom it may concern:

Be it known that I, ALFRED DWIGHT, of Springfield, in the county of Hampden and State of Massachusetts, have originated and 5 invented a new and useful Design in Blank Bill-Heads; and I do hereby declare that the following is a full, clear, and exact description thereof, reference being had to the accompanying drawing, forming a part of this specification.

A detail description of the design is as follows:

A is a straight line, located at the right and near the top, having at its right the figures 15 "188" in the fanciful type. This I term the "date-line."

B is a panel designed to receive the name of the debtor, having upon its left the fanciful letter "M," and above and at the left of the 20 center the fanciful work H.

A panel, D, similar to the panel B, and designed to receive the name of the creditor, is located a short distance below and at the right of the center of the panel B, and connected therewith in the manner shown by the short 25 diagonal panel C. Upon the left of the panel D are the words "Bought of" in the fanciful type, having the ornamentation shown. At the right of the panel B, and above the panel D, are the ornamental lines and curves E. Below 30 the panel D are the ornamental lines F and G, and at the right the ornamentation I.

Having therefore described my design, what I claim is—

The design for a bill-head in blank, as shown 35 and described.

ALFRED DWIGHT.
